(57) **CLAIM**

The ornamental design for a liquid receptacle, as shown and described.

DESCRIPTION

FIG. 1 is a top, front, and right side perspective view of a liquid receptacle according to our new design;

FIG. 2 is a rear elevation view thereof;

FIG. 3 is a front elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The dot-dash broken lines represent boundaries of the claimed design and form no part of the claimed design. The dash-dot broken lines depict portions of the liquid receptacle that form no part of the claimed design.

1 Claim, 3 Drawing Sheets
